United States Patent

Des. 239,049

Patented Mar. 2, 1976

239,049

TOOTHPICK DISPENSER

Darrell D. Fish, Timonium, Md., assignor to Universal Synergetics, Inc., Pennsauken, N.J.

Filed May 28, 1974, Ser. No. 473,494

Term of patent 14 years

Int. Cl. D20—99

U.S. Cl. D52—2 B

Fig. 1

Fig. 2

Fig. 3

FIG. 1 is a top left front perspective view of a toothpick dispenser showing my new design;

FIG. 2 is a top plan view thereof; and

FIG. 3 is a front elevational view thereof.

The rear and right sides, not shown, are substantially identical to those shown.

I claim:

The ornamental design for a toothpick dispenser, substantially as shown and described.
